UNITED STATES PATENT OFFICE

2,645,492

SHUFFLEBOARD TYPE GAME APPARATUS

Lyndon A. Durant, Chicago, Ill., assignor to Royal Patent Corporation, Chicago, Ill., a corporation of Illinois

Application February 9, 1950, Serial No. 143,309

8 Claims. (Cl. 273—126)

1

This invention relates to certain new and useful improvements in shuffleboard type game apparatus in which a puck is manually propelled over the playing field in the direction of switch elements disposed contiguous pins simulating bowling pins, whereby upon closing of the switches by the puck, a score is electrically recorded.

More specifically, the invention has to do with an arrangement for returning the spent puck to the player for replay.

An object of the invention is the provision of an arrangement whereby the foregoing is accomplished in a simple and effective manner and by means which may be economically manufactured.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a fragmentary longitudinal, vertical sectional detail view of a game apparatus showing my invention associated therewith;

Fig. 2 is a sectional detail view taken substantially on line 2—2 of Fig. 1;

Fig. 3 is a fragmentary plan view of the return trough taken substantially on line 3—3 of Fig. 2;

Fig. 4 is a fragmentary perspective view of the delivery end of the puck return trough;

Fig. 5 is a fragmentary sectional detail view taken substantially on line 5—5 of Fig. 6;

Fig. 6 is a sectional detail view taken substantially on line 6—6 of Fig. 5;

Fig. 7 is a fragmentary plan view taken substantially on line 7—7 of Fig. 5.

A puck is a disc, circular in plan view, to provide relatively flat sides for smooth movement over the playing surface over which it is manually propelled. This invention has to do with an arrangement for automatically returning the puck to the player after the same has been played over the playing surface. To accomplish the foregoing objects of the invention, I provide an amusement game apparatus which comprises a cabinet 10 comprising a top wall 11 providing a playing surface 12, over which the puck is manually propelled. At the end 13 of the playing field, farthest away from the player, are arranged a plurality of switch elements 14 which are adapted to be engaged by the puck to effect operation of an electrically controlled scoring mechanism (not shown). This mechanism has not been shown or described because it constitutes no part of the present invention. Adjacent this end 13

2

of the playing field, is an upright cabinet 15 within which the scoring mechanism is housed. The bottom wall of this cabinet is indicated at 16. The end 13 of the playing field terminates short of this wall 16 to provide a transversely extending gutter 17.

This gutter 17 is provided by vertically positioned spaced walls 18 and 19. The upper end or mouth portion of the gutter has a curved wall 20 extending from the wall 18 so as to direct the puck 21 to a position, between the walls 18 and 19, with its edge disposed upon a track 22 arranged between the walls 18 and 19 at the lower longitudinal edges thereof. This track 22 is preferably formed of rubber so as to cushion the impact received thereby from the puck 21. The upper end portion of the wall 19 is curved toward the end 13 of the playing field so as to provide a guide for the movement of the puck from the playing field into the gutter 17. The track 22 is supported between the walls 18 and 19 by suitable nut-receiving bolts 23, which bolts connect the walls 18 and 19 to a depending apron 24 provided by the wall 16 of the cabinet.

Supported adjacent one of the side walls 25 of the cabinet, is an inclined return trough 26. The pucks are delivered to the receiving end 27 of this trough by a curved connecting trough 28 which connects the return trough 26 to the gutter 17. The bottom wall 29 of the return trough is V-shaped in cross section, as best shown in Fig. 2, whereby to reduce the friction between the bottom wall of the return trough and the puck, as the puck rolls down the return trough. Extending transversely of the cabinet between the side walls thereof and in spaced relation with respect to each other, are partitions 30 which support the return trough 26, these partitions being fixedly secured within the cabinet in any suitable manner. The outlet or discharge end 31 of the return trough 26 communicates with a slot 32 formed in the front wall 33, of the cabinet. Secured to this front wall 33 of the cabinet is a supporting tray or cup 34 into which the puck 21 moves from the return trough and from which cup the puck 21 may be taken for replay upon the playing surface 12.

Above the switches 14 in spaced relation with respect to the playing surface 12, is a horizontally positioned plate 35 which carries a plurality of pins 36 simulating in miniature form standard bowling pins.

The conventional shuffleboard game now on the market and which in its operation requires the use of pucks, is substantially long, making it

inconvenient for the player to retrieve a played puck. By incorporating my invention in such a game, the puck is automatically returned to the player. As it slides off the end 13 of the playing surface 12 into the gutter 17, it assumes an upright position, with its edge disposed upon the track 22 for rolling therewith to the connecting trough 28 for passage into the return trough 26 and thence into the cup 34. The rubber track 22 in addition to absorbing the shock of the puck when engaged thereby, also reduces the noise caused by the puck engaging such track. In its movement down the return trough 26, the puck engages a relatively small portion of the bottom wall 17, thereby reducing the frictional engagement between the puck and the bottom wall 29 of the return trough 26, with the result that the speed of movement of the puck in its travel to the cup 34, is substantially increased.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. In combination, a game apparatus in which there is a cabinet having a wall providing a substantially horizontally arranged playing surface, an inclined gutter at one end of the playing surface and extending transversely with respect thereto, an inclined return trough within the cabinet and extending substantially at right angles with respect to the gutter and having communication with the lower end of said gutter, a receiving cup carried by the cabinet in communication with the discharge end of the return trough, said gutter including a mouth extending wholly transversely of said playing surface in the plane thereof and adjacent said one end of the playing surface to receive a puck from said playing surface, said mouth having a wall portion extending transversely of the playing surface and curved in the direction thereof for directing said puck into said gutter in a substantially upright position with respect to the bottom of the gutter.

2. In combination, a game apparatus in which there is a cabinet having a wall providing a substantially horizontally arranged playing surface, an inclined gutter at one end of the playing surface and extending transversely with respect thereto, an inclined return trough within the cabinet and extending substantially at right angles with respect to the gutter and having communication with the lower end of said gutter and having a bottom wall substantially V-shaped in cross section, a receiving cup carried by the cabinet in communication with the discharge end of the return trough, said gutter including a mouth extending wholly transversely of said playing surface in the plane thereof and adjacent said one end of the playing surface to receive a puck from said playing surface, said mouth having a wall portion extending transversely of the playing surface and curved in the direction thereof for directing said puck into said gutter in a substantially upright position with respect to the bottom of the gutter.

3. In a game device having a playing surface over which a disk-shaped playing piece may be

slidably propelled generally in one direction and a storage station for the playing piece located at the end from which the playing pieces are propelled, means for returning the playing piece to the storage station comprising channel-forming means extending generally in said direction and inclined downwardly toward the storage station for guiding the playing piece rollably on edge, a playing piece receiving hopper disposed beneath the plane of the playing surface and having a playing piece receiving opening adjacent a marginal edge of a portion of said playing surface, said hopper comprising an approximately vertical wall extending transversely of said direction, a second wall extending transversely of said direction opposite said vertical wall, said second wall sloping from the top progressively inwardly of said hopper to approach the vertical and being spaced from the vertical wall a distance not closer than the thickness of the playing piece, and a bottom inclined toward said channel forming means, said walls and bottom forming a guide channel extending transversely of said direction, and a curved channel-forming section connecting said guide channel and said channel-forming means.

4. In a game device having a playing surface over which a disk-shaped playing piece may be slidably propelled generally in one direction and a storage station for the playing piece located at the end from which the playing pieces are propelled, means for returning the playing piece to the storage station comprising channel-forming means extending generally in said direction and inclined downwardly toward the storage station for guiding the playing piece rollably on edge, a playing piece receiving hopper disposed beneath the plane of the playing surface and having a playing piece receiving opening adjacent a marginal edge of a portion of said playing surface, said hopper having an approximately vertical wall extending transversely of said direction and a second wall extending transversely of said direction opposite said vertical wall, said second wall from its top edge inwardly being progressively inclined to approach the vertical and to approach said vertical wall to form therewith a guide channel of a width slightly greater than the thickness of a playing piece so as to receive a playing piece in an edge position only and said guide channel having a bottom inclined toward said channel-forming means, and a curved channel-forming section connecting said guide channel and said channel-forming means.

5. In a game device having a playing surface over which a disk-shaped playing piece may be slidably propelled generally in one direction and a storage station for the playing piece located at the end from which the playing pieces are propelled, means for returning the playing piece to the storage station comprising channel-forming means extending generally in said direction and inclined downwardly toward the storage station for guiding the playing piece rollably on edge, a playing piece receiving hopper disposed beneath the plane of the playing surface and having a playing piece receiving opening adjacent a marginal edge of a portion of said playing surface, said hopper comprising an approximately vertical wall extending transversely of said direction, a second wall inclined downwardly toward said vertical wall and extending transversely of said direction to form a guide channel and means forming a bottom for said channel 75 slightly wider than the thickness of a playing

piece and inclined downwardly toward said channel-forming means, and means forming a curved channel section connecting said guide channel and said channel-forming means.

6. In a game device having a playing surface over which a disk-shaped playing piece may be slidably propelled generally in one direction and a storage station for the playing piece located at the end from which the playing pieces are propelled, means for returning the playing piece to the storage station comprising a channel-forming means extending generally in said direction and inclined downwardly toward the storage station for guiding the playing piece rollably on edge, a playing piece receiving hopper disposed beneath the plane of the playing surface and having a playing piece receiving opening adjacent a marginal edge of a portion of said playing surface, said hopper having an approximately vertical wall extending transversely of said direction, a second wall portion extending transversely of said direction inclined downwardly toward said vertical wall with the lower edge of said wall portion spaced from said vertical wall a distance less than the diameter of the playing piece and greater than the thickness of said playing piece to form a guide channel supporting the playing piece generally in on edge position, and a member forming a bottom for said hopper inclined toward said channel-forming means, said channel-forming means being connected at its higher end in playing piece receiving relation to the lower end of said hopper.

7. In a game device having a playing surface over which a disc-shaped playing piece may be slidably propelled generally in one direction and a storage station for the playing piece located at the end from which the playing pieces are propelled, means for returning the playing piece to the storage station comprising a channel-forming means extending generally in said direction and inclined downwardly toward the storage station for guiding the playing piece rollably on edge, a playing piece receiving hopper disposed beneath the plane of the playing surface and having a playing piece receiving opening adjacent a marginal edge of a portion of said playing surface, said hopper having an approximately vertical wall extending transversely of said direction and a second wall forming the opposite side of the hopper also extending transversely of said direction, said second wall sloping from the top progressively inwardly of said hopper to approach the vertical and together with said verti-

cal wall forming a guide channel extending transversely of said direction and provided with a bottom inclined toward said channel-forming means and just slightly wider than the thickness of a playing piece, and a curved channel-forming section connecting said guide channel and said channel-forming means.

8. In a game device having an elongated playing surface with a transversely extending opening therein and a scoring zone immediately adjacent the opening over which a disc-shaped playing piece may be propelled generally longitudinally thereof and across the scoring zone and a storage station for the playing piece near the end 10 of the playing surface remote from the scoring zone, means for returning the playing piece to the storage station comprising a playing-piece-receiving hopper disposed beneath the opening in the playing surface and having an approximately vertical wall extending transversely of the playing surface, a second wall extending transversely of the playing surface opposite said vertical wall, said vertical wall having a curved section extending above and to the rear of the playing 15 surface, said second wall having beneath the playing surface a portion inclined progressively to approach the vertical and said vertical wall, and an inclined bottom slightly wider than the thickness of a playing piece, said walls and bottom 20 forming a guide channel extending transversely of the playing surface, and means forming an inclined channel for guiding a playing piece while rolling on its periphery, said channel-forming 25 means being connected at one end in playing-piece-receiving relation to the lower end of said hopper and extending from there in a direction generally longitudinally of the game device playing 30 surface.
